SHOE POLISH COMPACT

William J. Bowen and William R. White,
Berkeley, Calif.

Application October 22, 1945, Serial No. 623,804

1 Claim. (Cl. 15—135)

1

The invention relates to a cleaning and polishing outfit, and more especially to a shoe polishing compact device.

The primary object of the invention is the provision of a device of this character, wherein a collapsible tube containing fluid polishing material held within the latter is dispensed therefrom so that it can be conveniently applied to footwear, for the cleaning and polishing of the latter by the device when in use.

Another object of the invention is the provision of a device of this character, wherein the body of the same forms a chamber for accommodating the tube containing the polishing material, and this body carries a dauber for spreading and applying the material to the footwear, the device in its entirety being of novel construction, and through the latter there is avoided any waste of the material when being delivered to the footwear for polishing purposes.

A further object of the invention is the provision of a device of this character, wherein the collapsing of the tube is accomplished in a unique manner for the forcing of the material therefrom to effect dispensing of the latter as needed, while the device is adapted for hand use in the polishing operation thereof.

A still further object of the invention is the provision of a device of this character, which is simple in construction, thoroughly reliable and efficient in operation, strong, durable, readily and easily handled, preserving the material content, to eliminate drying thereof when the device is not in use, assuring the proper dispensing of the material while in use, and inexpensive to manufacture.

With these and other objects in view, the invention consists in the features of construction, combination and arrangement of parts as will be hereinafter more fully described, illustrated in the accompanying drawings, which disclose the preferred embodiment of the invention, and pointed out in the claim hereunto appended.

In the accompanying drawings;

Figure 1 is a side view of the device constructed in accordance with the invention.

Figure 2 is a top plan view.

Figure 3 is a view similar to Figure 2 with the cover removed, and being partly broken away.

Figure 4 is a view similar to Figure 3, with portions thereof being further broken away.

Figure 5 is an enlarged sectional view taken

2

on the line 5—5 of Figure 1 looking in the direction of the arrows.

Figure 6 is a sectional view taken on the line 6—6 of Figure 1 looking in the direction of the arrows.

Figure 7 is an enlarged fragmentary vertical longitudinal sectional view showing in detail the tube collapsing mechanism.

Similar reference characters indicate corresponding parts throughout the several views in the drawings.

Referring to the drawings in detail, A designates generally the device constructed in accordance with the invention, and in its entirety, as will be hereinafter more fully described.

The device A comprises a hollow elongated body 10, preferably made from metal, although it may be made from any suitable material, to provide a bottom 11, sides 12, and ends 13, respectively, the sides and ends being in upstanding relation to the bottom. Internally of this body 10 is a chamber or compartment 14, while extending from one end 13 of such body is the stem 14' of a dauber 15, having tufted bristles 16, the stem being rearwardly angled to the plane of the bottom 11 so that the dauber is at an elevation thereto.

Removably fitted over the body 10 is a cover section 17, which is frictionally spring latched thereto as at 18. The opposite sides of this cover section 17 have formed in their side walls finger gripping depressions 19, to enable a firm hold to be gotten thereon when using the polishing cloth or pad 20 covering the bottom 11 of the body 10, and such cloth or pad is held smooth and fast in any suitable manner, it being removable.

Extending through the dauber 15 and its stem 14' is a dispensing pipe 21, which opens through the said dauber 15 at one side thereof, the other end of the pipe 21 being carried into the chamber or compartment 14 for detachable coupling therewith the nipple end 22 of a collapsible tube 23 containing polishing material, which is adapted to be dispensed through the pipe 21 when the tube is being collapsed in a manner presently described.

The bottom 11 has formed therein close to the sides 12 of the body 10, a pair of parallel perforated tracks 24, constituting gear racks for a pair of toothed rack gears 25 formed at opposite ends of a presser roller 26, its arbor 27 beyond the ends thereof being detachably engaged in slots 28a in springy hanger bearings 28 formed internally of the body 10, and this roller effects the collapsing of the tube 23 when such roller is oper-

ated. The tube 23 is disposed within the chamber or compartment 14 superimposed on the bottom 11 of the body 10, with the roller 26 positioned to roll over the said tube.

Slidably fitting a suitable clearance in one side 12 of the body 10 next to the stem 14' is a spring tensioned push button 29, which has pivotal connection at 30 with one arm of a bell-crank 31, pivotally mounted on a pin 38 in a bracket 39, its other arm being pivotally connected at 32 with an elongated ratchet pawl or dog 33, co-acting with the ratchet feed wheel 34 on the roller 26, so that when the button 29 is depressed, it will operate the said dog or pawl, to effect a step-by-step rotation of the roller 26, causing the collapsing of the tube 23, and thereby forcing the material therein through the pipe 21 for the dispensing of such material outwardly of the dauber for the application of the material to footwear for the cleaning and polishing of the same, the dauber being for spreading the material on the footwear, while the cloth or pad is for the polishing thereof. The button 29 is tensioned by a spring 35 which normally outwardly projects this button from the body 10.

The outer end of the pipe 21 is normally closed by a pivoted closure piece 36, its pivot being indicated at 37 on the dauber 15.

It is of course understood that the bearings 28 allow the roller 26 to advance longitudinally of the chamber or compartment 14 for effecting full collapsing of the tube 23, the roller being advanced by the engagement of the gears 25 engaging the tracks 24 and following the same.

Each time the button is pressed inward the bell-crank 31 draws the pawl 33 forward and the teeth of the pawl engage the teeth of the ratchet wheel 34 causing the roller 26 to rotate and travel forward. The pawl 33 is slidably held in an inverted U-shaped sheath or guide 40 that extends from the bracket 39 and holds the teeth of the pawl in engagement with the teeth of the ratchet wheel 34, and as the button is released the spring 35 moves the button outward wherein the bell-crank pushes the elongated pawl 33 backward and the guide 40 moves upward so that the pawl moves upward and the teeth thereof pass over the teeth of the ratchet wheel 34, whereby the collapsible tube of shoe polish is mashed slightly to feed a small amount of polishing paste therein each time the button 29 is pressed inward.

What is claimed is:

In a shoe polisher, the combination, which comprises a rectangular-shaped box-like base having side walls and a bottom and provided with a substantially hollow arm extending from one end

with a brush carried at the end of the arm, a tube positioned in the arm extending from the brush to the base to the inner end of which the open end of a collapsible tube of shoe polish may be attached, the side walls of said base formed with resilient arcuate upper edges extending inwardly and downwardly within the base and provided with parallel longitudinally disposed slots in the downwardly extending parts thereof, a roller having gears on both ends and a ratchet wheel on one end positioned in the base with the downturned parts of the side walls resiliently engaging the gears, said base having parallel rows of openings in the bottom thereof positioned to register with the gears at the ends of the roller providing gear racks therefor, an arbor on which the roller is mounted positioned in the base with the ends thereof extending into the slots in the downturned parts of the side walls and with the gears meshing with the said gear racks, an elongated pawl having teeth in the lower edge positioned in the base, a sheath in which the said pawl is slidably mounted positioned to maintain the teeth of the pawl in meshing relation with the teeth of the ratchet wheel of the roller, a bracket at the end of the base from which the brush arm extends on which the said sheath is mounted, a bell-crank pivotally mounted in said bracket with one arm pivotally connected to the elongated pawl, a button slidably mounted in a side wall of the base with an enlarged end extending from the base, means pivotally connecting the inner end of the button to the other arm of the bell-crank whereby inward movement of the button actuates the pawl whereby the roller is moved to force polish from the collapsible tube to the brush, and a cover for the said base.

WILLIAM J. BOWEN.
